SPARK PLUG

Filed Sept. 5, 1934

WITNESS:

UNITED STATES PATENT OFFICE

2,008,617

SPARK PLUG

Ivan Lampitt, Pekin, Ill., assignor of one-fourth
to Mrs. Edwin A. Lampitt, Pekin, Ill.

Application September 5, 1934, Serial No. 742,819

4 Claims. (Cl. 123—169)

This invention relates to spark plugs for internal combustion engines and similar devices and has for the primary object the provision of a device of this character wherein the electrical 5 spark thereof may be materially increased to extend over a greater area and in annular formation which will cause thorough and complete burning of the fuel in the engine and eliminate the customary practice of employing dual ignition systems and spark plugs to the engine.

With these and other objects in view this invention consists in certain novel features of construction, combination and arrangement of parts to be hereinafter more fully described and 10 claimed.

For a complete understanding of my invention, reference is to be had to the following description and accompanying drawing, in which

Fig. 1 is a side elevation, partly in section, illustrating a spark plug constructed in accordance 20 with my invention.

Figure 2 is a top plan view illustrating the same.

Figure 3 is a side elevation, partly in section, 25 illustrating a modified form of my invention.

Figure 4 is a top plan view illustrating the same.

Figure 5 is a plan view, partly in section, illustrating an electrode plate.

Referring in detail to the drawing, the numeral 30 1 indicates a metallic body constructed similarly to the body of a conventional type of spark plug and has mounted therein the insulator 2, carrying the central electrode 3. A metallic externally 35 screw threaded sleeve 4 is connected to the end of the body 1 by a non-magnetic sleeve 5 and is spaced from the end of the body 1 to form an annular groove 6. A perforated electrode plate 7 forms an integral part of the electrode 3 and

40 is arranged within the annular groove having its periphery spaced from the walls of said groove to form a spark gap of annular formation. The sleeve 4 projects outwardly of the non-magnetic sleeve 5 and provides a medium for attaching the 45 spark plug to an engine in the usual manner.

An electro-magnet 8 is arranged adjacent the body 1 and the terminal posts 9 thereof are adapted to be connected into an electric circuit. The core of the electromagnet is in the form of 50 sectional clamps 10, one of which is applied to the sleeve 4 and insulated from the non-magnetic sleeve 5 while the other is applied to the body, as shown in Figure 1. The split clamps form the north and south poles to the electro-magnet

55 so that during the use of a spark plug or when

connected in a high tension circuit and the electro-magnet energized the spark between the plate 7 and the walls of the groove 6 will be caused to spread to cover a greater area thereby producing a more efficient arc or spark than heretofore possible to obtain from a spark plug of a conventional construction. The increased spark will more effectively ignite and burn the fuel in the cylinder of the engine. The spark or arc is compelled to pass through the magnetic field 10 of the electro-magnet 8 which has a tendency to suck the spark across the gap defined by the plate 7 and the walls of the annular groove.

Referring to my modified form of invention, the body of the spark plug is indicated by the character 11 and its threaded portion has threaded thereto a non-magnetic sleeve 12 and threaded to the sleeve 12 is a metallic shell 13 spaced from the body 11 and is provided at one end with an inwardly extending annular flange 14. The insulator of the body 1 is indicated by the character 15 and carries the central electrode 16 to which is secured an annular cup-shaped plate 17, the flange of which is spaced from the flange 14 forming a spark gap of annular formation. The 25 plates 17 and 7 are perforated to equalize pressure on opposite sides thereof.

A series of electromagnets 18 are associated with the body and the shell 13 and are connected in an electric circuit in any suitable manner. The cores of the electromagnets are of substantially U-shape and are indicated by the character 18'. The ends of the cores are secured in 30 sockets formed in the body 11 and the shell 13. The spark produced at the spark gap is compelled to pass through the magnetic field of the electromagnets 18.

Having described the invention, I claim:

1. A spark plug comprising a metallic body, an insulator carried by said body, a central electrode carried by said insulator, a metallic sleeve secured to and spaced from the body to form an annular groove, a circular electrode plate integral with said electrode and arranged in said groove to form an annular spark gap, and electro-magnetic means between said sleeve and body and connected in an electric circuit for spreading and increasing the area covered by the spark between the walls of said groove and the 45 plate.

2. A spark plug comprising a metallic body, an insulator carried by said body, an electrode carried by the insulator, a metallic element detachably secured to the body and spaced therefrom, 50

- a circular plate carried by the electrode and co-operating with the body and metallic element in forming an annular spark gap, and electro-magnetic means connected to the body and to the metallic element.
3. A spark plug comprising a metallic body, an insulator carried by said body, an electrode carried by the insulator, a metallic element detachably secured to the body and spaced therefrom, a circular plate carried by the electrode and co-operating with the body and metallic element in forming an annular spark gap, an electro-magnet arranged adjacent the body and including
- 10

a core having sectional end portions applied to the metallic element and to said body.

4. A spark plug comprising a metallic body, an insulator carried by said body, an electrode carried by the insulator, a metallic element detachably secured to the body and spaced therefrom, a circular plate carried by the electrode and co-operating with the body and metallic element in forming an annular spark gap, a series of electro-magnets each including a winding and a core 10 with the ends of said core secured to the body and the metallic element.

IVAN LAMPITT.
